(57) **CLAIM**

The ornamental design for an enclosure for a tablet computer, as shown and described.

DESCRIPTION

FIG. 1 is a frontal perspective view of an embodiment of a new design for an enclosure for a tablet computer;

FIG. 2 is a front view of the enclosure shown in FIG. 1;

FIG. 3 is a rear view of enclosure shown in FIGS. 1 and 2;

FIG. 4 is a top view of the enclosure shown in FIGS. 1-3;

FIG. 5 is a bottom view of the enclosure shown in FIGS. 1-4;

FIG. 6 is a first (left) side view of the enclosure shown in FIGS. 1-5;

FIG. 7 is a second (right) side view of the enclosure shown in FIGS. 1-6; and,

FIG. 8 is a frontal perspective view depicting the enclosure of FIGS. 1-7, including the a back side of the front cover shown in FIGS. 1 and 2 and various internal features.

Broken lines have been included in the drawings to illustrate environment, non-limiting embodiments of respective dimensions, and embodiments of additional features that an enclosure for a tablet computer may include. The broken lines form no part of the claimed design.
